UNITED STATES PATENT OFFICE.

BEN N. YOUNGKEN OF LOS ANGELES, CALIFORNIA.

CASING ELEVATOR.

1,424,548.

Specification of Letters Patent. Patented Aug. 1, 1922.

Application filed August 30, 1920. Serial No. 406,910.

To all whom it may concern:

Be it known that I, BEN N. YOUNGKEN, a citizen of the United States, residing at Los Angeles, in the county of Los Angeles 5 and State of California, have invented a new and useful Casing Elevator, of which the following is a specification.

This invention relates to casing elevators and is particularly directed to the type of 10 elevators generally employed for raising, lowering or supporting well casings, sucker rods or pump tubing.

An object of the invention is to provide an elevator which is of simple and durable 15 construction, which can be easily and quickly manipulated, and which will efficiently fulfill all the requirements of heavy duty service demanded of devices of this character.

Another object is to provide a two part 20 hinged unit elevator having a latch for the gate which is positively retained in latching position by a shoulder or coupling of the casing or rod engaged by the elevator.

Another object is to provide a safety pawl 25 which is associated with the latch and which must be released before the latch can be disengaged from the gate.

Another object is to maintain a smooth 30 unbroken upper surface of the elevator.

Various other objects and advantages 35 will be more fully apparent from the following description of the accompanying drawings, which form a part of this disclosure, and which illustrate a preferred form of embodiment of the invention.

Of the drawings:

Figure 1 is a top plan view.

Fig. 2 is a front elevation.

Fig. 3 is an enlarged detail section on 40 line $\alpha^3-\alpha^3$ of Fig. 1.

Fig. 4 is a perspective view of one end 45 of the body, showing the latch receiving recess and the spring receiving recess thereof.

Fig. 5 is a detail perspective view of the 50 gate latch, looking at its under side; and

Fig. 6 is a detail perspective view of the safety pawl.

The body portion of the elevator com- 55 prises a substantially U-shaped casing 2, the medial concave inner surface 3 of which

forms an approximate half circle and is adapted to engage the casing or rod to which the elevator is applied. Diametrically opposed ears 4-4 extend outwardly from 55 the body and are provided with transverse orifices 5-5 to receive the bails 6-6 which may be of any of the many well known types. To facilitate a lateral removal of the bails I provide removable blocks 7-7 60 forming the outer walls of said orifices, each held in place by a bolt 8 extending vertically through the respective ear 4 and the block.

Adjacent one end of the concave surface 65 of the body I provide bearings 9-9 projecting laterally and relatively spaced to form a suitable opening to receive a hinge bearing 10 of a gate 11 which is journaled to swing on a pivot pin 12. The inner concave surface 13 of the gate is curved to conform to the surface 3 of the body and when the gate is closed registers therewith to form a vertical concentric bore adapted to closely embrace the object to which the 75 elevator is applied. The free end of the gate has a lateral tongue 14 which engages and rests upon a shelf 15 on the body, when the gate is in closed position.

The gate 11 is latched in closed position 80 by a gate latch 17 which is positioned or embedded in a recess 18 formed in the upper surface of the body and is pivoted to swing vertically on a pivot pin 19. The hook nose 20 of the latch 17 engages over 85 the tongue 14 of the gate to latch the gate in closed position. A latch spring 21 is positioned within a recess 22 in the body with one end engaging a stud 24 on the body and the other end engaging a pin 25 90 on the latch, said spring exerting a normalizing tension on the latch.

To positively maintain the latch 17 in latching position when the elevator is in use, I provide said latch with a lateral lug 95 26 which extends laterally in the recess 18 to a point approximately flush with the concave surface 3 of the body. When the elevator engages a casing, the shoulder or coupling thereof will engage the lug 26 and 100 maintain the gate latch 17 against unlatching movement.

To guard against an accidental unlatching of the gate I provided a safety pawl 30 which is associated with the gate latch and which must be operated previous to an unlatching of the gate latch. The outer nose end of the gate latch 17 is bifurcated to receive the pawl 30 which is pivoted on a transverse pivot pin 31 and which also has a hook nose 32 adapted to enter a recess 33 formed in the gate tongue 14 and engage beneath the horizontal surface 38 of the abutment formed thereby. The body of the pawl 30 has a transverse opening 34 positioned concentric to the pivot pin 31 and a stop stud 35 carried by the latch 17 extends through said opening. A pawl spring 36 in the opening 34 engages the stud 35 and the opposite end of the wall of the opening and tends to yieldingly maintain said pawl in normal position, the stud 35 serving to limit the movement of the pawl.

The outer end of the pawl has lateral flanges 37 forming stops limiting the upward movement of the pawl relative to the latch and also providing an extended surface to facilitate a convenient manipulation.

With the gate closed and the nose 20 of the latch 17 engaged over the tongue of the gate, as shown in Fig. 3, the gate will be maintained in closed position, and the nose 32 of the safety pawl 30, engaging within the recess 33 of the gate tongue 14, will prevent a vertical releasing movement of the latch. To release the gate it is first necessary to raise the safety pawl upwardly, to the position indicated in dotted lines in Fig. 3, to withdraw its hook nose 32 horizontally from the recess 33, after which the gate latch 17 may be raised out of engagement with the gate tongue. This operation may be accomplished in a single movement by pressing upwardly upon the under surface of the free end of the pawl 30, the first part of the movement disengaging the pawl and bringing its stop flanges 37 against the outer end of the latch 17 and a continuation of the movement carrying the latch and pawl upwardly free of the gate.

This construction of gate latch and safety pawl provides a double or compound latch in which the vertically movable latch functions to retain the gate in closed position and the horizontally movable pawl functions to maintain the latch against accidental displacement, or vertical movement.

This contributes to a safe operation of the elevator and provides a structure which will maintain its effective functions even when the parts become considerably worn through long and severe usage.

I claim:

1. An elevator of the character described comprising two members hingedly united, a vertically movable latch pivoted on one

member and engaging the other member to maintain the members in closed relation, and a pawl pivoted on the latch and engaging one of said members to maintain the latch against vertical movement, the pawl being adapted to swing horizontally in a latch releasing movement.

2. An elevator of the character described comprising a body and a gate hinged thereto to swing horizontally, the gate having a horizontal abutment, a vertically movable latch pivoted on the body and having a hook end adapted to engage over the free end of the gate to maintain it closed, and a pawl pivoted on the latch and adapted to engage beneath the abutment to maintain the latch against vertical gate releasing movement.

3. An elevator of the character described comprising a body and a gate hingedly united, and a compound latch pivoted on the body and having a member adapted to engage over the free end of the gate and a second member cooperating with the gate to maintain the first member in latching engagement.

4. An elevator of the character described comprising a body and a gate hingedly united, a spring operated latch carried by the body and adapted to engage the free end of the gate to maintain it in closed position, and a spring operated pawl adapted to engage the gate to retain the latch against movement.

5. An elevator of the character described comprising a body and a gate hingedly united, a latch pivoted on the body and having a hook nose adapted to engage the free end of the gate, said latch having a bifurcated free end, and a pawl positioned between the furcations of the latch and pivoted thereto, said pawl cooperating with the gate to maintain the latch against movement.

6. An elevator of the character described comprising a body and a gate hingedly united, means for maintaining the gate in closed position, and a second means carried by the first named means and cooperating with the gate to maintain said first means against a gate releasing movement.

7. An elevator of the character described comprising a body and a gate hingedly united, the gate having an abutment, and a compound latch pivoted on the body and having a member adapted to engage over the free end of the gate to maintain it closed and a second member adapted to engage said abutment to maintain the first member against a gate releasing movement.

8. An elevator of the character described comprising a body and a gate hingedly united, a vertically movable latch pivoted on the body and engaging the free end of the gate to maintain the gate in closed position, and a pawl pivoted on the latch and

engaging the gate to maintain the latch against vertical gate releasing movement, the pawl being adapted to be swung horizontally to release the latch.

5 9. A latch device for well elevators comprising a latch member having a fulcrum and a downwardly extending hook nose at its free end, and a pawl carried by the free

end of said member and having a laterally extended hook nose.

Signed at Los Angeles, California this 23d day of August 1920.

BEN N. YOUNGKEN.
